MANICURE KIT

Stuart S. Joslyn, Chester, Conn., assignor to C. J.
Bates & Son, Chester, Conn., a firm

Application October 31, 1950, Serial No. 12,787

Term of patent 7 years

(Cl. D87—3)

To all whom it may concern:

Be it known that, I, Stuart S. Joslyn, a citizen of the United States, residing at Chester, in the county of Middlesex and State of Connecticut, have invented a new, original, and ornamental Design for a Manicure Kit, of which the following is a specification, reference being had to the accompanying drawings, forming part hereof:

Fig. 1 is a perspective view of a manicure kit in the closed position;

Fig. 2 is a perspective view of a manicure kit in the open position.

The back of the kit is substantially plain.

My design for a manicure kit is characterized by the elongated cylindrical ends in association

with the rectangular front and back sides and the oval shaped mirror at the upper inner face of the back side of the kit.

I claim:

The ornamental design for a manicure kit, as shown and described.

STUART S. JOSLYN.
